DESIGN FOR A JEWELRY DISPLAY BOX

Howard S. Scholes, Cranston, R. I., assignor to J. J. White Manfg. Co., Providence, R. I.

Application January 24, 1935, Serial No. 55,041

Term of patent 3½ years

To all whom it may concern:

Be it known that I, Howard S. Scholes, a citizen of the United States, residing at Cranston, in the county of Providence, State of Rhode Island, have invented a new, original, and ornamental Design for Jewelry Display Boxes, of which the following is a specification, reference being had to the accompanying drawing, forming part thereof.

I claim:—

The ornamental design for a jewelry display box as shown and described.

HOWARD S. SCHOLES.
